UNITED STATES PATENT OFFICE.

HAROLD L. WATSON, OF LANCASTER, PENNSYLVANIA.

BROODER.

Application filed January 31, 1918. Serial No. 214,636.

To all whom it may concern:

Be it known that I, HAROLD L. WATSON, a citizen of the United States, and a resident of Lancaster, county of Lancaster, 5 State of Pennsylvania, have invented certain new and useful Improvements in Brooders, of which the following is a specification, reference being had to the accompanying drawing.

10 My invention relates generally to brooders for chickens and other fowl or birds and more particularly to brooders for little chicks hatched in incubators.

15 Among the principal objects of my invention is to provide a colony brooder adapted to take care of and successfully protect a large number of chicks, in which the necessary heat is generated by the combustion of anthracite or bituminous coal or other suitable solid fuel and embodying temperature controlling means whereby the temperature may be automatically maintained with great exactness at any desired point within limits.

20 Further objects of my invention are to provide a brooder embodying the foregoing characteristics which is adapted to supply the chicks with a maximum quantity of fresh air while maintaining a suitable temperature and affording ample protection 25 from floor drafts or other currents of air detrimental to their well being; to provide a brooder comprising heating means adapted to maintain an even rate of combustion during long periods of time with a minimum amount of care and attention and without danger of the fire becoming entirely extinguished; which shall be extremely economical in the amount of fuel consumed; and in which the fuel supply is required to 30 be replenished only at maximum intervals of time.

Further objects of this invention are to provide automatic means for drawing off impure air from the hover of the brooder 45 into the heater to also act to check the action of the fire, thus providing means for performing the double function of removing impure air from the brooder and simultaneously checking the action of the heater.

50 In the accompanying drawing, Fig. 1 is a central vertical section of one embodiment of my invention, certain of the parts being shown in elevation for the sake of clearness, said figure also showing in broken

lines certain of the parts in various positions assumed during the operation of the invention as hereinafter described; Fig. 2 is a top plan view of the form of the invention shown in Fig. 1, but on a reduced scale; Fig. 3, a fragmentary vertical section, and 60 Fig. 4 a fragmentary top plan view, both illustrating certain details of the invention.

Referring now to that form of the invention shown in the drawing, the same comprises a heater preferably arranged for 65 burning either hard or soft coal, or other solid fuel, and having a body 2 forming a combustion chamber 3 above the base 4, comprising an ash pit 5 and supporting the fire pot which may preferably be substantially circular in form and comprise an upwardly divergent rim or wall 7 surrounding a plurality of movable horizontally extending grate bars 8 supported in the center of the fire pot and arranged for axial oscillation in any suitable manner to permit the fire to be shaken when desired, as, for example, by means of suitable intermeshing gearing (not shown) actuated by means of a removable crank adapted for engagement 80 with a squared stud 10 projecting through the wall of the base 4, the grate bars being preferably so arranged that they may not be completely inverted, thereby preventing accidental dumping of the fire during the 85 shaking operation. The base 4 may be preferably of substantially frusto-conical form and contain a layer of asbestos or other suitable insulating material 12 adjacent its bottom 13 to protect the floor of the building 90 in which the brooder is located, and may also be provided with a suitable opening, closed by a swinging ash door 14, for the removal of the ashes accumulating in chamber 5. The body 2 of the heater, surrounding the combustion chamber 3, may be also preferably of frusto-conical form, its greatest diameter being adjacent the fire pot and its smaller at its upper extremity, which is closed by a top 15 preferably integral with 95 the side of the body and provided with a suitable charging hole 17 closed by a removable lid 18 provided with a handle 18' of any convenient form, and also with a sleeve 19 for the attachment of the smoke 100 pipe or chimney 20, the body of the heater being preferably secured to the base by suitable stay bolts 23, or in any other conven-

ient manner, so that it is maintained in unitary operative relation therewith. It will be noted that the area of the grate bar surface is preferably considerably less than the 5 greatest projected area of the combustion chamber, so that, when the latter is filled with fuel the portion thereof directly subjected to the current of air drawn in from the ash pit 5 during the process of combustion, is materially less in area than the 10 greatest projected area of the body of the fuel contained in the combustion chamber, so that the fuel is caused to burn most rapidly at its center leaving a body of unburned 15 or relatively very slowly burning fuel, adjacent the wall of the combustion chamber, thus materially modifying the amount of heat radiated from the exterior thereof while permitting the fuel to be consumed at its 20 center with sufficient rapidity to prevent the fire from going out. As it is extremely desirable in this class of brooders that the heater shall not get excessively hot and thus raise the temperature under the hover unduly, and on the other hand that the fire 25 shall not be kept so low as to be in danger of going out, the construction hereinbefore described by means of which a relatively hot fire of small diameter can be maintained 30 at the center of the fuel surrounded by a wall of unburned or slowly burning fuel whereby the radiation from the heater is modified, is of material advantage.

In the normal operation of the heater, the 35 door 14 is kept continuously closed and for the purpose of admitting to the ash pit a sufficient quantity of air to support combustion, the side of the base 4 is provided with a draft opening 25 over which is securely 40 positioned an outwardly extending preferably substantially horizontal arm 26, the inner end of the arm being provided with a boss 27 formed with an upwardly opening chamber 28 which communicates with 45 the draft opening 25, the mouth of the chamber being adapted to be closed by a disk 30, as hereinafter described, to control the passage of air to the ash pit and thence to the combustion chamber 3.

50 For the purpose of additionally controlling the rate of combustion, the combustion chamber is supplied adjacent its upper extremity with a suitable preferably substantially L-shaped damper 32, comprising 55 plates 33 and 34 respectively adapted to control apertures 35 and 36 in the side and top of the combustion chamber, the damper being preferably pivoted on suitable horizontally extending trunnions 38 to permit its 60 movement in a vertical plane when actuated preferably as hereinafter described. For the purpose of preventing the fuel from interfering with the movement of the damper, the top 15 may be provided with a plurality 65 of downwardly depending teeth or fingers

40 so positioned as to prevent the fuel when introduced through the charging opening 17 from piling up adjacent the damper, and thereby interfering with its freedom of movement.

A suitable hover or deflector 43, of frustoconical form, preferably formed of sections of sheet metal secured together by rivets or bolts 44, is rigidly affixed to a flanged ring 45 adapted to removably engage the upper 70 peripheral edge of the heater, and adjacent the lower edge of the hover are provided a plurality of radial outwardly extending arms 48 serving to support adjacent their outer extremities a suitable curtain ring 49 75 over which is draped a depending curtain 50 formed, preferably, of suitable fabric, the curtain and ring being preferably removably secured to the ends of the arms as by the bolts and nuts 52. It will be evident 80 that as the curtain is thus maintained in spaced relation with the lower edge of the hover, an annular space or opening 55 is provided between the curtain and the hover, thus permitting the chicks when congregated 85 inside the curtain to receive a plentiful supply of fresh air while receiving the heat radiated from the heater and deflected downwardly by the hover, although fully protected by the curtain from the detrimental 90 effects of floor drafts. To afford a convenient means of raising the hover and curtain out of the way when removing ashes from the heater, or when it is desired to sweep or 95 clean beneath the hover, suitable cords 56, 100 57 may be attached to the latter and led over suitable pulleys 58 attached to the ceiling of the building, by means of which the hover and curtain may be readily raised to assume substantially the position shown in 105 broken lines in Fig. 1. A thermometer 59 may be arranged to project through the hover in such manner that the temperature beneath the hover as indicated by it may 110 conveniently be observed from above the hover.

To effect the automatic regulation of the rate of combustion within the heater, suitable means are provided comprising, in the form of the invention shown, a suitable diaphragm thermostat 60 preferably adjustably supported from the arm 26 as by a set screw 62 passing through the arm, thus permitting the vertical adjustment of the thermostat as desired, a stud 63 projecting 115 from the thermostat being arranged to bear on one arm of a T-shaped counterpoise 64 supported on a knife edge bearing 65 adjacent the outer extremity of arm 26. A plurality of suitably hinged connected 120 rods 66, 67 and 68 serve to connect the counterpoise with an arm 69 preferably formed integrally with the damper 32, a spring 70 being preferably interposed 125 between rods 67 and 68 to permit a slight 130

relative longitudinal movement between said rods for a purpose to be hereinafter described. The rod 67 is preferably arranged to pass through a small aperture 73 in the boss 27, and through chamber 28, and is provided with a projection 74 which serves to normally support the disk 30 which is slidably mounted on the rod 67. Hence the downward movement of the rod from 10 the position shown in full lines in Fig. 1 is not limited by contact of the disk with boss 27, but may freely continue after such contact, the rod merely sliding through the disk which rests upon the boss.

15 The parts being constructed and assembled preferably substantially as hereinbefore described, the operation of the invention may be briefly described as follows: The hover and curtain being conveniently raised, as 20 shown in dotted lines in Fig. 1, the fire may be started in the heater in the ordinary way, the parts being preferably so adjusted that the draft opening 25 will be open and the damper at the top of the combustion chamber closed. The hover may 25 now be lowered into its operative position, as shown in full lines in Fig. 1, in which the radiation from the heater will raise the temperature beneath the hover until a point 30 is reached at which expansion of the thermostat causes the gradual depression of the adjacent arm of the counterpoise and consequent downward movement of the rods connecting the counterpoise with the damper, to simultaneously draw disk 30 toward 35 the mouth of cavity 28 in boss 27, to diminish the amount of air admitted through draft opening 25, and also to gradually open damper 32 to admit air to the top of the 40 combustion chamber, thus checking the fire. In case the expansion of the thermostat should continue after disk 30 contacts with boss 27, rod 67 may freely slide through the disk, and in a similar manner further expansion of the thermostat after damper 32 45 is fully opened, merely results in temporary elongation of the spring 70, thus relieving the parts from undue strain and the possibility of consequent injury which might 50 otherwise occur. When the fire is sufficiently reduced to lower the temperature in the vicinity of the thermostat and cause it to contract, a reverse action takes place, damper 32 being gradually closed and disk 30 moved 55 upwardly to admit air to the draft opening, thereby again increasing the fire and in turn the heat beneath the hover. A substantially constant predetermined temperature may thus be maintained beneath the hover, which 60 temperature may be varied as desired, between limits, by suitable adjustment of the thermostat by means of screw 62, the fire being automatically increased or diminished 65 through the operation of the damper and regulation of the draft opening when the

temperature in the vicinity of the thermostat falls or rises below the predetermined point.

In the operation of the invention, the foul and most highly heated air accumulates in the upper part of the hover and as damper 32 is arranged to admit to the combustion chamber air drawn from beneath the hover as well as air from the exterior thereof, the opening of the damper serves 70 to promptly free the hover from this accumulation which is rapidly drawn through the combustion chamber and up the chimney 20. Of course, the damper 32 could be formed of separate dampers for each of the 75 openings 35 and 36, and each could be independently controlled by thermostats within the brooder if desired. This action serves to materially assist in preserving the 80 purity of the atmosphere beneath the hover and consequent health of the chicks, and also assists in maintaining a substantially 85 even temperature at all points beneath the hover. It will also be seen that the damper 32 which causes the air drawn from beneath 90 the hover to enter on top of the fire in the combustion chamber 3, acts as a check damper on the fire and hence performs the 95 two functions of relieving the impure air from beneath the hover and checking the action of the heater. Moreover, as the hot- 100 test portion of the air beneath the hover is immediately drawn into the heater and out of the hover and fresh air is drawn into the bottom of the hover adjacent the thermostat to take its place, the prompt response of the thermostat, and, in turn, the fire controlling means, to variations in temperature beneath the hover and consequent 105 automatic control of the fire within an extremely narrow range of limits is assured.

It will be understood that when necessary the fuel in the combustion chamber may be replenished through the opening 17, without the necessity of raising the hover 110 from its operative position, and that owing to the construction hereinbefore described whereby the hottest portion of the fire is maintained at the center of the mass of fuel and in a sense insulated from the walls 115 of the heater by a body of unburned or slowly burning fuel, the fire may be kept at a sufficient intensity to guard against its becoming extinguished without causing the air beneath the hover to become excessively 120 hot, and also with a minimum consumption of fuel, and the temperature of the air beneath the hover be maintained at a substantially constant point, determined by the adjustment of the thermostat, over long 125 periods of time without any attention from the operator whatsoever.

The action of the curtain 50 will, it is believed, be fully understood from the preceding description where it will be seen 130

that the same protects the chicks from relatively strong floor drafts, and, by reason of the top opening, or annular channel 55 between the bottom of the hover 43 and the top edge of the curtain 50, fresh air is supplied to the chicks in the manner indicated. It will also be seen that by means of the cords 56 and 57, both the hover 43 and curtain 50 may be simultaneously moved from the heater for any purpose desired, as, for example, for facilitating the removal of the ashes from the fire pit of the heater, or for any other reason.

While I have herein illustrated and described a single embodiment of my invention with a considerable degree of particularity, I do not thereby desire or intend to limit myself specifically thereto, as various changes and modifications may be made in the details of construction and arrangement of the various parts thereof, as desired, without departing from the spirit and scope of the invention as defined in the appended claims.

Having thus described my invention, what I claim and desire to protect by Letters Patent of the United States, is:

1. In a brooder, the combination of a heater having a combustion chamber, a hover surrounding said heater, a check damper for controlling the admission of air from beneath said hover to said combustion chamber, thermostatic means for controlling said damper, a curtain surrounding said hover and spaced therefrom to provide an air inlet leading to the thermostatic means, and means for operatively positioning said curtain and said hover relative to said heater.

2. In a brooder, the combination of a heater having a combustion chamber, a conically shaped hover surrounding said heater, a check damper for controlling the admission of air from beneath said hover to said combustion chamber, a damper for controlling the admission of air to said heater below said combustion chamber, thermostatic means for controlling said dampers, a curtain surrounding said hover and spaced therefrom, means for connecting said curtain with said hover, and means for supporting said hover and said curtain whereby said hover and curtain may be supported and raised simultaneously.

3. In a brooder of the character described, a hover formed substantially conical in shape, means for providing heat, said means being arranged below the hover, a curtain surrounding the hover and spaced therefrom, means for supporting the curtain, and means for connecting the curtain with the hover whereby the hover may be supported and raised simultaneously with the curtain.

4. In a brooder of the character described, a hover formed substantially conical in shape, means for providing heat, said means being arranged below the hover, a curtain surrounding said hover and spaced therefrom, means for connecting said hover and said curtain, and means for supporting said hover and curtain whereby said hover may be supported and raised simultaneously with said curtain.

In witness whereof, I have hereunto set my hand this 30th day of January, 1918.

HAROLD L. WATSON.
